ATTORNEY

UNITED STATES PATENT OFFICE.

JAMES NORVAL BANNOCHIE, OF BUFFALO, MINNESOTA.

LOCK.

Application filed March 30, 1923. Serial No. 628,867.

To all whom it may concern:

Be it known that I, JAMES N. BANNOCHIE, a citizen of the United States, residing at Buffalo, in the county of Wright and State 5 of Minnesota, have invented new and useful Improvements in Locks, of which the following is a specification.

This invention relates to locks and more particularly to a lock designed principally 10 for use on the doors of automobiles, and an object of the invention is to provide a lock structure which is comparatively simple and is operated either by means of a push button or by means of the handle for 15 the door, and which lock structure is designed to permit the door to be closed and locked without requiring the usual slamming operation necessary for properly closing doors having locks of approved type 20 thereon, such as now commonly in use.

Another object of the invention is to provide a lock as specified which may be locked so that it cannot be unlocked or released by 25 operation of the usual unlocking means.

A further object of the invention is to 30 provide a lock as specified which includes a pivotally mounted locking pawl adapted to engage and cooperate with a stationary locking wedge to lock the door in closed position, which locking pawl is moved into 35 locking position by the closing movement of the door and springs into unlocking position under action of its spring upon release of locking means to permit the door to be opened.

Other objects of the invention will appear in the following detailed description taken in connection with the accompanying drawings wherein:—

40 Fig. 1 is an inside view of a vehicle door showing the improved lock associated therewith.

Fig. 2 is a vertical section through the door showing the lock in elevation.

45 Fig. 3 is a detail horizontal section on the line 3—3 of Fig. 2 showing the locking pawl in open or unlocked position.

Fig. 4 is a view similar to Fig. 3 showing the door closed and the locking pawl in 50 locking position.

Fig. 5 is a fragmentary vertical section taken on the line 5—5 of Fig. 2.

Fig. 6 is a detail perspective of the lock employed in the lock.

Fig. 7 is a detail perspective view of the locking pawl employed in the lock.

Referring more particularly to the drawings, the improved lock comprises a suitable casing 1 which may be inserted into a door A and while the lock is particularly 60 designed for automobile doors it may be used in connection with any other type of door where it is found practical or as found applicable.

The improved lock comprises a locking 65 pawl 2 which is pivotally mounted upon a suitable pivoting pin 3. The pin 3 is carried by the transverse plates 4 which are formed on the housing 1. The locking pawl 2 is provided with a substantially V shaped 70 recess 5 in its outer face which faces the opening 6 in the housing 1. When the door is open and the pawl 2 is in unlocking position the projection 7 is positioned in the path of the locking projection 8 which 75 is carried by the plate 9. The plate 9 is in turn carried by the door frame 10.

When the pawl 2 is in open or unlocking position and the door A is closed the side 11 of the projection 7 or substantially V shaped 80 opening 5 will be engaged by the locking projection 8 which will swing the pawl 2 upon its pivot into the position shown in Fig. 4 of the drawings at which time both of the angled sides of the substantially V 85 shaped opening 5 will be in engagement with the angled sides 12 of the projection 8, as clearly shown in Fig. 4 of the drawings which locks the door closed. When the pawl 2 is swung into locked position, the 90 spring 14 which engages about a pin 15 on one end of the projection 16 and about a pin 17 carried by the housing, is tensioned and it is held under tension by means of the upward movement of the locking bolt 18. 95 The locking bolt 18 is slidably supported for vertical movement and it is urged into its upper position by means of a spring 19 which is coiled about the pin 3 and engages the horizontal projection or plate 20 which 100 is formed upon the upper end of the locking bolt 18. The locking bolt 18 is provided with a transversely extending recess 21 into which the projection 16 on the locking pawl

2 moves when the locking pawl is in open position, as shown in Fig. 3 of the drawings, however, when the locking pawl 2 is swung into its locking position, the projection 16 will move out of the recess 21 which will permit the spring 19 to flex and move the locking pawl 18 upwardly moving the opening 21 out of registration with the projection 16 which will prevent unlocking movement of the pawl 2 and consequently prevent opening of the door A.

A guiding flange 23 is struck down from the partition 4 to guide the movement of the lower end of the locking bolt. An operating rod 24 is connected to the plate 20 and extends upwardly therefrom extending out of the door A into the interior of the vehicle and passing through a suitable guide 25. A thumb nut or button 26 is mounted upon the upper end of the rod 24.

When the locking pawl 2 is held in locked position by the locking bolt 18 which is, as previously stated at such time in its uppermost position and it is desired to unlock the door, downward pressure is applied to the thumb nut 26 which forces the rod 24 downwardly which in turn forces the locking bolt 18 downwardly, against the tension of the spring 19 and into the position shown in Fig. 2 of the drawings which moves the transverse recess 21 into registration with the projection 16 and allows the pawl 2 to be rocked and the door A opened.

If the lock is employed upon the door of a motor vehicle of the closed type, such as a "sedan," "coupe" or the like, a handle 27 may be provided on the outer side of the door which handle is pivotally supported by means of a suitable support 28. The handle 27 has the end adjacent to its pivot projecting the door into the housing 1 so that upon rocking movement of the handle 27 upon its pivot 30 the locking bolt 18 will be forced downwardly to permit unlocking of the door.

It may be desirable at times to lock the door closed so that it cannot be opened either by operation of the handle or by downward pressure on the rod 24 and to permit this locking a locking lever 31 is provided which is pivotally mounted upon the pin 3 and projects through a slot 32 in the housing 1 so as to permit one end of the lever to be engaged by the operator. The end of the lever 31 which is positioned within the housing 1 may be enlarged as shown at 33 and it is adapted to be moved into the transverse recess 21, above the door partition plate 4 so as to prevent the locking bolt 18 from being forced downwardly from operation of either the handle 27 or rod 24.

It is, of course, to be understood that the invention may be constructed in other manners and the parts associated in different re-

lations and, therefore, I do not desire to be limited in any manner except as set forth in the claims hereunto appended.

Having thus described my invention what I claim is:

1. A lock comprising a pivotally mounted locking pawl, a spring normally urging said pawl into unlocking position, a slidably mounted locking bolt, means normally urging said locking bolt into locking position to lock said pawl in locking position, means for moving said locking bolt into unlocking position and permit said pawl to be moved into unlocking position, and a locking lever for preventing operation of said locking bolt by said last named means.

2. In a lock, a pivotally mounted locking pawl, a projection on said pawl, a slidably mounted locking bolt, said locking bolt provided with a recess to receive said projection to permit said pawl to move into unlocking position, means for urging said locking bolt into position to move said recess out of registration with said projection for holding said pawl in locking position, and means connected to said locking bolt for moving it to bring said recess in registration with said projection, a pivotally mounted locking lever adapted to be moved into the recess in said locking bolt to prevent movement of the locking bolt.

3. A lock comprising a pivotally mounted locking pawl, a projection on said pawl, a slidably mounted locking bolt provided with a transverse recess adapted to receive said projection to permit movement of the locking pawl into unlocking position, a transverse plate on said locking bolt, a spring engaging said plate and normally urging the locking bolt into position to move said recess out of projection receiving position and for holding said pawl in locked position, and operating means engaging said transverse plate for moving the locking bolt to bring said recess in registration with said projection.

4. A lock comprising a pivotally mounted locking pawl, a projection on said pawl, a slidably mounted locking bolt provided with a transverse recess adapted to receive said projection to permit movement of the locking pawl into unlocking position, a transverse plate on said locking bolt, a spring engaging said plate and normally urging the locking bolt into position to move said recess out of projection receiving position and for holding said pawl in locked position, an operating rod connected to said transverse plate for operating said locking bolt, a pivotally supported handle, and a projection on said handle adapted to engage said transverse plate to operate said locking bolt.

In testimony whereof I affix my signature.

JAMES NORVAL BANNOCHIE.
